UNITED STATES PATENT OFFICE.

THOMAS H. SMITH, OF KENDALLVILLE, INDIANA.

ADJUSTABLE VEHICLE-SEAT.

SPECIFICATION forming part of Letters Patent No. 741,077, dated October 13, 1903.

Application filed April 11, 1903. Serial No. 152,189. (No model.)

To all whom it may concern:

Be it known that I, THOMAS H. SMITH, a citizen of the United States, residing at Kendallville, in the county of Noble and State of Indiana, have invented a new and useful Adjustable Vehicle-Seat, of which the following is a specification.

This invention relates to passenger-vehicles, and has for its object to provide an auxiliary seat adapted to be projected into suitable position relative to the vehicle-seat to support an additional passenger without inconvenience to the occupants of the ordinary seat; and the invention consists in certain novel features of the construction whereby the desired results are attained, as hereinafter shown and described, and specified in the claims.

In the drawings illustrative of the invention, in which corresponding parts are denoted by like designating characters, Figure 1 is a longitudinal sectional elevation with the auxiliary seat projected or in operative position. Fig. 2 is a perspective view of the improved device, together with a portion of the vehicle-floor, with the auxiliary seat withdrawn.

This device may be attached to any of the ordinary makes of carriages and buggies, but is more particularly applicable to buggies or similar vehicles having level floors beneath the seat and in which it is often desired to provide accommodations for a third person upon seats constructed only for two, and for the purpose of illustration the device is shown applied to a vehicle-body 10 of the ordinary construction, with a seat 11 and its "fall" or valance-curtain 12 depending in front of the seat.

Disposed upon the floor of the vehicle, beneath the seat, are spaced guide-tracks 13 14, in which a traveler 15 is movably mounted, the traveler having an upwardly-extending portion 16, as shown.

Pivottally connected to the portion 16 is a standard 17, having the auxiliary seat 18 upon its free end and adapted when the traveler is drawn forward and the standard elevated, as in Fig. 1, to project over the center of the seat 11 at a sufficient distance above the cushions thereon to provide a seat for a third person without inconvenience to the ordinary occupants of the vehicle-seat.

The standard 17 is provided with an elongated aperture 19, through which a button 20, mounted for rotation upon the traveler, is adapted to pass when the standard is elevated, and when this occurs and the button is rotated one-fourth a revolution the standard will be "locked" in its vertical position, as will be obvious.

When in its elevated position, the standard and traveler will come in front of the fall or seat-valance 12, and when withdrawn beneath the seat 11 the auxiliary seat and other parts will be entirely concealed by the valance, as will be obvious. Thus the presence of the device will not detract from the appearance of the vehicle, as it will be entirely concealed when not in use.

The rear portions of the guide-tracks 13 14 will preferably be provided with a housing or cover 21 to not only protect the traveler and its attachments when in their withdrawn position, but also to protect the contents of the vehicle-box when the device is employed in vehicles having space for merchandise or other goods in the rear of the seat. The cover member will also be employed in vehicles having two permanent seats to prevent the feet of the occupants of the back seat from coming in contact with or being struck by the traveler when withdrawn beneath the forward seat.

The auxiliary seat may be readily withdrawn and "set" in operative position by one of the occupants of the seat 11 and without changing his position, and may likewise be released and returned to its position beneath the seat in the same manner. Provision may thus be made for the extra passenger without inconveniencing or disturbing the other passengers, as will be obvious.

The whole structure is very simple, cheap, and easily applied, and may be attached to the vehicle without structural change of the vehicle.

Changes in the minor portions of the structure may be made without departing from the principle of the invention or sacrificing any of its advantages.

Having thus described the invention, what I claim is—

1. The combination with a vehicle-body and its seat, of a longitudinally-disposed guide-

way beneath the seat, a standard slidably mounted in said guideway, carrying a seat and adapted to slide forward in front of said permanent seat and to be elevated in front thereof, said standard being also adapted to be withdrawn beneath said permanent seat.

2. The combination with a vehicle-body and its seat of a guideway disposed upon the vehicle-floor beneath the seat, a traveler slidably engaging said guideway, a standard movably connected to said traveler and having a seat upon its free end and adapted to slide forward and be elevated in front of the seat and adapted to be withdrawn beneath said seat, substantially as described.

3. The combination with a vehicle-body and its seat of a guideway disposed upon the vehicle-floor beneath the seat, a traveler movably engaging said guideway, a standard movably connected to said traveler and having a seat upon its free end and adapted to slide forward and be elevated in front of the seat and to be withdrawn beneath the seat, and means carried by said traveler for locking said standard and its seat in their elevated position, substantially as described.

4. The combination with a vehicle-body and its seat of a guideway disposed upon the vehicle-floor beneath the seat, a traveler movably engaging said guideway, a standard movably connected to said traveler and having a seat upon its free end and adapted to be elevated in front of the seat and withdrawn beneath

the seat, said standard having an elongated aperture, and a catch rotatively mounted upon said traveler and adapted to engage said aperture and detachably lock said standard relative to said traveler, substantially as described.

5. The combination of a vehicle-body and its seat of a flexible curtain depending in front of said seat, a guideway upon the vehicle-floor in the rear of said curtain, a traveler mounted for movement upon said guideway, a standard movably connected to said traveler and carrying a seat upon its free end and adapted for elevation in front of said seat and its curtain or for withdrawal beneath the seat and in the rear of said curtain, substantially as described.

6. The combination with a vehicle-body and its seat, of a guideway disposed upon the vehicle-floor beneath the seat, a folding seat slidably mounted on said guideway, and a housing inclosing said guideway and forming a covering for said folding seat when in its withdrawn position, substantially as described.

In testimony that I claim the foregoing as my own I have hereto affixed my signature in the presence of two witnesses.

THOMAS H. SMITH.
